UNITED STATES PATENT OFFICE.

JOHN A. ROBERTSON, OF ROCHESTER, NEW YORK, ASSIGNOR TO EASTMAN KODAK COMPANY, OF ROCHESTER, NEW YORK, A CORPORATION OF NEW YORK.

MOTION-PICTURE-FILM REEL.

Application filed October 26, 1922. Serial No. 597,144.

To all whom it may concern:

Be it known that I, JOHN A. ROBERTSON, a citizen of the United States of America, residing at Rochester, in the county of Monroe and State of New York, have invented certain new and useful Improvements in Motion-Picture-Film Reels, of which the following is a full, clear, and exact specification.

10 This invention relates to photography and particularly to reels adapted for use in motion picture apparatus, and has for its object to provide a simple and efficient reel.

To these ends the improvements are directed 15 particularly to the means for attaching the end of the film strip to the reel; to means for providing such a device in which there are no movable parts or springs to hold the film strip; to means for readily directing 20 the film strip into position to be held by the reel hub; and to means for holding an end of the film band while the band is folded to attach it temporarily to the hub. With these and other objects in view the invention 25 consists in certain improvements and combinations of parts, all as will herein-after be more fully described, the novel features being pointed out in the claims at the end of the specification.

30 In a film reel for motion picture work it is desirable not only that the film be held firmly while the film is being wound upon the reel, but that the end of the film be free to leave the reel when the film is being wound therefrom at considerable speed.

In the drawings, in which like reference characters denote like parts throughout:

Fig. 1 is a side elevation of a film reel constructed in accordance with, and illustrating one form of my invention;

Fig. 2 is a section on line II-II of Fig. 1; and

Fig. 3 is a fragmentary side elevation of a portion of my reel with one flange removed.

The reel consists of side flanges 1 and 2 supported upon a hub 3 by means of tongues 4 extending from the hub into slots 5 in the flanges, where they are expanded to hold the 50 parts together. Flange 1 is provided with a series of small apertures 6 and large apertures 7 one of which is V-shaped at 8 to facilitate loading. This flange is, in the form shown, used facing the operator. An 55 aperture 9 forms a shaft bearing. Flange 2

differs from 1 in having a single series of small perforations 10, being without the larger apertures. Like flange 1, flange 2 has a central shaft bearing 11 and it has also a series of small apertures 12 of which one or more may engage a film reel driving mechanism. This structure is largely standard practice.

Coming now to my invention, the hub 3 is formed of a single piece of sheet metal of sufficient thickness to retain its shape, and having one edge sheared straight across as at 13. This forms a sharp bending edge for the film band F. The metal is bent into the form of a drum and has the opposite end 14 of the metal strip offset from edge 13 a sufficient distance for the film band to pass between the ends. The ends, where spaced from each other are substantially concentric with each other, thus providing an open passageway or slot 15 extending to the interior of the hub on a line approximately at a tangent to the hub. The metal is bent at 16 from the periphery of the drum and after a reverse bend 17 terminates in a square edge 18 beneath the upper edge 13. This portion 17 is substantially concentric with the outer wall of the drum.

The operation of my reel is as follows. The film strip F' is held at a tangent to hub 3 and pushed into the passage 15, where, as will be obvious, one face f of the strip will be curled by and will lie adjacent to the inner face 19 of hub 3. The offset metal ends cause the film to assume this position. Then the reel may be turned in the direction of the arrow Fig. 3 or the reel may be held still and the film F turned in the direction of the broken arrow about edge 13 causing a sharp bend in the film at B, and causing face f of the film to lie adjacent to the outer face 20 of hub 3. This will hold the film firmly while the convolutions are wound upon the reel. It should be noticed that passage 15 with the straight edge 13 causes the film to be bent practically upon itself with but little more than the thickness of the metal hub between the faces of the film.

It is also important that this structure, when used as a supply reel, permits the film end to withdraw from hub 3 when the film is completely unwound, even though the reel is rotating at high speed. The bend B being released as the last convolution unwinds from the reel allows the film to reas-

sume the position shown at F' from which it will draw the end from the slot.

It is to be noted that the straight edges 13 and 14 extend completely across the reel 5 and are not bent, curved or toothed to clasp or indent the film, the film when bent as shown, being held by its natural elasticity with its opposite faces in firm contact with the overlapping metal edges.

10 When film band or film is referred to in this specification and in the claims its use in a broad sense is intended, that is, I mean it to include the film itself on any support such as pyroxylin or paper, or the paper or 15 other leader strip such as is used in some instances.

Having thus described my invention, what I claim as new and desire to secure by Letters Patent is:

20 1. In a reel for motion picture film, the combination with two side flanges, of a hub for supporting these flanges, the hub comprising a drum-shaped member having a portion of its wall offset to form a slot, one 25 portion of the wall lying beneath another portion thereof, and being positioned substantially concentric therewith, whereby the walls of the slot will direct a film into the drum-shaped hub at substantially a tangent 30 thereto.

2. In a reel for motion picture film, the combination with flanges of a hub supporting the flanges and having a film attaching device, the hub consisting of a drum-shaped 35 sheet of metal having one edge offset below the other edge and spaced therefrom to permit the entrance of strip material into the drum, a curved portion of the metal strip leading from the periphery of the drum to 40 the edge which is offset below the other edge and forming a guideway to direct a strip of material into the drum, the position of the walls of the drum-shaped hub being such

that a film may be directed into the hub substantially at a tangent thereto.

3. In a reel, the combination with flanges, of a hub carrying the flanges, said hub being made from strip material bent into a cylinder and having straight ends, one end of the strip being offset from the other end, and partially lying beneath said other end, the ends of the strip material being spaced one from the other and substantially parallel to each other, whereby a film may be held on the spool by a sharp bend made by folding the film about the upper end of the strip material causing the film to lie adjacent to both surfaces of at least a portion of the strip material.

4. A motion picture film reel comprising 60 spaced flanges and a connecting hub, the hub being cylindrical and made of sheet material, and having a passage extending completely across it, one side of the passage being a straight edge and at the periphery of 65 the hub and the other side of the passage being formed by a piece of material having a straight edge and extending within and beyond the first mentioned edge, thereby forming a passage into which a strip of 70 film may be thrust in a direction substantially tangential to the hub.

5. A motion picture film reel comprising 75 spaced flanges and a connecting hub, the hub comprising a single piece of sheet metal bent into tubular form, and one of the ends of the piece of sheet metal being bent inwardly and extended beyond the other end and substantially concentric therewith, whereby there is formed a passage between such ends 80 into the hub substantially tangential to the hub, and the ends having straight edges extending completely across the hub.

Signed at Rochester, New York, this 23rd day of October 1922.

JOHN A. ROBERTSON.
